CLAIM

The ornamental design for a portable bonfire candle, as shown and as described.

DESCRIPTION

FIG. 1 is a front perspective view of a portable bonfire candle showing our new design in a cylindrically shaped container;

FIG. 2 is a top view thereof;

FIG. 3 is a bottom view thereof;

FIG. 4 is a front side view thereof, the back side being a mirror image thereof.

FIG. 5 is a left side view thereof, the right side being a mirror image thereof;

FIG. 6 is a front perspective view of a portable bonfire candle showing our new design in an oval shaped container;

FIG. 7 is a top view thereof;

FIG. 8 is a bottom view thereof;

FIG. 9 is a front view thereof, the back view being a mirror image thereof;

FIG. 10 is a left side view thereof, the right side being a mirror image thereof;

FIG. 11 is a front perspective view of a portable bonfire candle showing our new design in a square shaped container;

FIG. 12 is a top view thereof;

FIG. 13 is a bottom view thereof;

FIG. 14 is a front side view thereof, the back side being a mirror image thereof;

FIG. 15 is left side view thereof, the right side being a mirror image thereof;

FIG. 16 is a front perspective view of a portable bonfire candle showing our new design in a rectangular shaped container;

FIG. 17 is a top view thereof;

FIG. 18 is a bottom view thereof;

FIG. 19 is a front view thereof, the back side being a mirror image thereof; and,

FIG. 20 is a left side view thereof, the right side being a mirror image thereof.
